Courtney et al., U.S. Office Action dated May 13, 2016, directed to Design U.S. Appl. No. 29/518,193; 8 pages.

Primary Examiner — Ruth McInroy

(74) Attorney, Agent, or Firm — Morrison & Foerster LLP

(57) **CLAIM**

We claim the ornamental design for a part of a vacuum cleaner, as shown and described.

DESCRIPTION

FIG. 1 is a perspective view of a part of a vacuum cleaner showing our new design;
 FIG. 2 is a front view thereof;
 FIG. 3 is a rear view thereof;
 FIG. 4 is a side view thereof;
 FIG. 5 is a side view of the opposite side of FIG. 4;
 FIG. 6 is a top view thereof; and,
 FIG. 7 is a bottom view thereof.
